(57) **CLAIM**

(73) Assignee: **Sunmark Glass, Inc.**, North York (CA)

The ornamental design for a surface ornamentation for a door window, as shown and described.

(**) Term: **14 Years**

DESCRIPTION

(21) Appl. No.: **29/147,516**

FIG. 1 is an elevational view of a surface ornamentation for a door window showing my new design; and, FIG. 2 is an elevational view of a second embodiment of a surface ornamentation for a door window showing my new design.

(22) Filed: **Aug. 31, 2001**

The broken line showing of the remainder of the door is for illustrative purposes only and forms no part of the claimed design. The depicted contrast in shading represents a contrast in appearance via color, texture, and/or luminance.
